UNITED STATES PATENT OFFICE

RYAN SADWITH, OF NEWARK, NEW JERSEY, ASSIGNOR TO NICHOLS PRODUCTS CORPORATION, OF HIGHLAND PARK, NEW JERSEY, A CORPORATION OF NEW JERSEY

OVEN

Application filed April 15, 1929. Serial No. 355,383.

This invention relates to ovens.

In the case of ovens of relative large size or length the construction becomes important. The oven must be of sufficient strength to render the proper service and yet must be of such a structure as to be efficient. In manufacturing plants it may become desirable to change the location of the oven and therefore the oven should be of such construction as to be capable of easy removal and re-erection.

One of the objects of this invention is to provide an oven that can be easily and cheaply erected and one that will permit of disassembly and easy removal and ready re-erection. Another object of the invention is to provide an entirely new type of structure which will give the proper strength and rigidity with relatively light weight. A further object of the invention is to eliminate structural construction. A further object of the invention is to form the oven from panels which are units not exceeding such size as will not permit of buckling under the heat. A further object of the invention is to provide an oven wherein the panels are interlocked, supported and sealed by posts. A further object of the invention is to provide an oven wherein the panels and posts are made of sheet metal filled with heat insulating material. Still another object of the invention is to provide with the aid of strengthening members the required rigidity and strength to the sheet metal posts and panels in order to eliminate structural members. A further object of the invention is to reduce heat losses by heat transmission or radiation from the interior.

Referring to the drawings:

Figure 1 is a view in elevation of a portion of an assembled oven embodying the principles of my invention.

Figure 2 is a view in side elevation of a portion of an oven of two panels in height.

Figure 3 is a cross section of Figure 1 along the line 3, 3, looking in the direction of the arrows.

Figure 4 is a broken detail view partly in section showing the arrangement of the vertical and horizontal posts in Figure 3.

Figure 5 is a sectional view along the line 5, 5, looking in the direction of the arrows of Figure 4.

Figure 6 is a top view of two panels with the vertical post inserted between.

Figure 7 is a top plan view of a single panel.

Figure 8 is a view in elevation, parts broken off and parts in section of a single panel along the line 8, 8, of Figure 7 looking in the direction of the arrows.

Figure 9 is a sectional view of Figure 8 along the line 9, 9, looking in the direction of the arrows.

Figure 10 is a sectional view along the line 10, 10, of Figure 8 looking in the direction of the arrows.

Figure 11 is a sectional view of a portion of a post along the line 11, 11, of Figure 12 looking in the direction of the arrows.

Figure 12 is a top plan view of a post.

Figure 13 is a sectional view of Figure 11 along the line 13 looking in the direction of the arrows.

Figure 14 is a detail view of the Z bar strengthening element for the panels.

In carrying out my invention I propose to provide panels 1 formed of two plates of sheet metal 2, 2', the top and bottom of each panel has secured to the panel walls 2, 2' angles 3, 3', also made of sheet metal. Spacing strips 4 are secured to angles 3, 3'. The means of securing the angles 3, 3', and the spacing strips 4 is preferably by welding although they may be secured in any other well known manner. Spacing strips 4 further function to retain the heat insulating material and by reason of their reduced area reduce the losses due to heat transference from the inside wall 2 to the outside wall 2'. Secured to the sides of each panel 1, adjacent the ends are strengthening Z members 5, 5', the walls 2, 2', being bent around the outside edge of the Z members 5, 5'. Spacing strips 6 join the Z members 5, 5', and function identically as spacing strips 4. The Z members 5, 5', at the top and bottom are notched as shown in Figure 14 to permit of the horizontal post abutting the vertical posts for strengthening purposes. The posts 7 have a somewhat similar construction. They are

90

95

100

formed of two channels 7', 7'', separated by spacers 8 which are likewise welded preferably to the exterior of the corresponding legs of each channel comprising the post 7 to form a post 7 as shown in top plan view in Figure 12. The vertical posts 7 may contain a stiffening angle 9 therein which angle can be utilized to secure the post to the supports of the oven and furnishes an element to which conveyors 14 or other machinery within the oven may be secured and supported. Such an arrangement of supporting the machinery within the oven is advantageous as the usual method of securing the same to the panels causes buckling and distortion of the panels unless special structural elements are built into the panels, which latter increases the cost.

In assembly the posts 7 are erected and bolted to the base 13 as shown in Figure 1, and the panels 1 are slid down between the posts 7, the side of each panel 1 covering half of the post so that the edges of each panel abut the edges of the adjacent panel.

It will thus be seen that the posts 7 operate as an interlocking element as well as a supporting element and of course as it is filled with heat insulating material also has the same function as the panel 1 in retaining the heat within the oven. In an oven of tiers of panels 1 horizontal posts 7 are inserted between the rows of panels 1, that is, at the top of the lower panel 1 and the bottom of the upper panel 1. When it is desired to build any oven of several tiers of panels 1 the vertical posts 7 extend throughout the height of the tiers and lend the required strength and rigidity to the structure. The horizontal posts form the interlocking means to prevent buckling and furnish a proper bearing surface for the panel 1 above. It will thus be seen that such a structure is adaptable to variation in the design of ovens and that the erection cost is very small in comparison to the structural type of oven. The use of the Z bar strengthening members 5, 5', in the panels 1 is also of considerable importance not only to render support in compression but also to furnish sufficient strength and rigidity so that the edges of the panels 1 will not readily become bent out of shape and thereby permit leakage of heat from within the oven around the posts 7, or leakage of dust into the oven in the same manner to the detriment of the articles under process.

In the case of an oven using only one height of panels 1 the channel space formed by angles 3, 3', and spacers 4 is filled with heat insulating material retained in place and sealed by sealer strips and angles 12 while in the case of an oven using tiers of panels 1 the bottom of the bottom row and the top of the top row are likewise packed 65 and sealed.

Variations in details might be made in the construction of the posts and panels and still fall within the scope of my invention.

It will thus be seen that I have invented a form of oven that can easily be erected or readily disassembled and re-erected and one which will have the proper strength and rigidity although of relatively light weight and which can be manufactured in units for assembly for divers types of ovens and which can be constructed with the minimum of 70 erection labor costs.

What I claim is:

1. An oven the walls thereof formed of metal panels, hollow posts of sheet metal supporting each panel, said posts of unit construction independent of the panels adapted for interlocking each panel and means for preventing the transfer of the heat through 80 said panels and posts.

2. An oven formed of sheet metal panels, each of said panels having an inner and an outer wall of sheet metal, sheet metal angles secured at the top and bottom of the inner and outer wall of each panel, spacer strips secured to said sheet metal angles to maintain the inner and outer wall in spaced relationship, strengthening bars of Z cross section secured to the two side edges of both the inner and outer wall of each panel, spacer strips secured to the two strengthening bars 90 Z cross section of each side to maintain the inner and outer wall in spaced relationship, a heat insulating filler between said inner and outer walls of each panel and maintained in position by said sheet metal angles, strengthening bars of Z cross section and spacer strips and posts independently constructed from said panels and adapted to support and interlock said panels.

3. An oven formed of panel units, each panel unit having an inner and an outer wall of sheet metal, means for maintaining said inner and outer wall in spaced relationship, heat insulating material between said inner and outer wall, strengthening bars of Z cross section secured to the two side edges of both the inner and outer wall of each unit to form a channel, each panel unit abutting the adjacent panel units on each side and having the channels forming a chamber to receive a supporting and interlocking post and a supporting post of built up sheet metal independent of the panels having heat insulating material therein fitting in said chamber.

4. In an oven formed of panel units, horizontal and vertical sheet metal posts to seal, interlock and support the panels and of independent construction therefrom, said posts formed from two pieces of sheet metal bent into channel shape, spacer strips secured to the corresponding arms of each of said channels to maintain the channels in spaced relationship.

5. In an oven formed of panel units, verti- 130

- cal posts to seal, support and interlock the panels, said posts built up of sheet metal independently constructed from the panels, means for heat insulating said posts, means 5 for reducing the transfer of heat from the inside wall of the post to the outside wall and a vertical stiffening angle through said post to secure machinery within the oven and to secure the post to the foundation.
- 10 6. An oven formed of tiers of panel units, each of said panel units formed of sheet metal, means for heat insulating the inner wall of each panel from the outer wall of the same panel, said panels having channels at their top, bottom and sides to receive posts, horizontal and vertical posts of sheet metal independently constructed from the panels to seal, interlock and support said panel units and means for heat insulating said posts.
- 15 7. An oven formed of tiers of panels units each of said panel units having means for heat insulating the inner wall of each panel from the outer wall of the same panel, said panels having corresponding channels in their top, bottom and sides, said channels when adjacent panels abut forming chambers to receive posts, hollow posts to interlock, seal and support said panels both vertically and horizontally in said chambers, said posts independently constructed and separable from said panels, and means for heat insulating said posts.
- 20 8. An oven formed of panel units, each of said panel units having means for heat insulating the inner wall of each panel from the outer wall of the same panel, said panels having corresponding channels in their sides, said channels when adjacent panels abut forming chambers to receive posts, hollow posts to interlock, seal and support said panels, said posts of separate construction from said panels and extending vertically the height of the oven.
- 25 9. An oven formed of tiers of panel units each of said panel units formed of sheet metal walls and having means for heat insulating the inner wall from the outer wall, horizontal means for interlocking, sealing and supporting said panels between and within the abutting panel units, vertical means for interlocking, sealing and supporting said panels between and within the abutting panel units, said vertical means for interlocking, sealing and supporting said panels extending 50 for all tiers of panels.
- 30 10. In an oven, panels therefor formed in units of standard size, said panels formed of sheet metal plates, sheet metal angles, spacer strips and strengthening bars of Z 55 cross sections, said plates connected by spacer strips of sheet metal at the top and bottom to said sheet metal angles secured to said plates, said spacer strips connected at the sides to said strengthening bars of Z cross section, the edges of the sides of said plates
- bent around the edges of the strengthening bars of Z cross section.
11. An oven formed of tiers of panel units, each of said panel units having means for heat insulating the inner wall of each panel from the outer wall of the same panel, said panels having corresponding channels in their top, bottom and sides, said channels when adjacent panels abut forming chambers to receive posts, hollow posts having insulating material therein to interlock, seal and support said panels both vertically and horizontally in said chambers, the vertical posts extending the full height of the tiers and the horizontal posts extending the width 70 of a panel between said vertical posts, said horizontal posts abutting said vertical posts.
